UNITED STATES PATENT OFFICE.

SILAS BENT RUSSELL, OF ST. LOUIS, MISSOURI.

FURNACE.

Application filed May 27, 1927. Serial No. 194,694.

This invention relates to furnaces and with regard to certain more specific features to thermostatically controlled smokeless furnaces. For burning bituminous coal.

5 Among the several objects of the invention may be noted the provision of a furnace having a plurality of grates and fire boxes adapted to operate alternately in series or in parallel; the provision of a furnace of the class 10 described equipped with improved draft control means, adapted to be manually set for series operation of the furnace when firing has been completed, and adapted to be automatically set for parallel operation of the 15 furnace after a predetermined temperature has been reached after firing; and the provision of a device of the class described which is simple in construction, economical and readily operable. Other objects will be in 20 part obvious and in part pointed out herein-after.

The invention accordingly comprises the elements and combinations of elements, features of construction, and arrangements of 25 parts which will be exemplified in the structure hereinafter described, and the scope of the application of which will be indicated in the following claims.

In the following drawings, in which is 30 illustrated one of various possible embodiments of the invention,

Fig. 1 is a horizontal section of the furnace taken on line 1—1 of Fig. 2, certain parts being omitted for clarity, the view being primarily diagrammatic;

Fig. 2 is a vertical section taken on line 2—2 of Fig. 1, certain portions being broken away;

Fig. 3 is a vertical section taken on line 40 3—3 of Fig. 2;

Fig. 4 is an isometric layout of one half of the damper control system used in the present invention the same being located outside the jacket to be described;

45 Fig. 5 is a fragmentary plan view showing a thermostatic controlling element; and

Fig. 6 is a fragmentary side elevation of a portion of said thermostatic controlling element.

50 Corresponding reference characters indicate corresponding parts throughout the several views of the drawings.

Smokeless furnaces, making use of two coal beds operating in series as regards draft, have 55 been heretofore devised, but difficulties have been encountered in preventing the second

grate of the second coal bed from burning out. This condition has existed because the hot burning gases passing from one grate passed through the other grate and tended to melt it down or burn it out.

The introduction of water grates to prevent this condition has not proved satisfactory, nor has the introduction of manually operated damper controls been successful.

Broadly, the present invention includes in a furnace a plurality of coal beds having damper controls adapted to be manually set for permitting either of alternate series operation of said coal beds, said damper controls also having thermostatically controlled means for resetting them after a period of time, so that they will cause parallel operation of said coal beds.

Referring now more particularly to Figs. 75 1 and 2, there is illustrated at numeral 1 a hot air heating jacket having an inlet 3 and circulating flues 5. This heating jacket 1 surrounds the improved furnace construction comprising two fire pots 7 and 9 carrying 80 grates 11 and 13 respectively. Below the grates 11 and 13 are ash pits 15 and 17 equipped with cleanout doors 19 and 21 respectively. The fire pots 7 and 9 are provided with firing doors 20 and 22, respectively, 85 above said grates.

The primary draft to the furnace is supplied through an inlet 23 having cross connections 25 and 27, which lead fresh air beneath the grates 11 and 13 respectively. 90 Dampers 29 and 31 are carried in the connections 25 and 27.

The fire pot 7 is connected from a point above its grate 11 to a point below the grate 13 of the fire pot 9 by way of a cross-connecting flue 33 having therein a damper 35; and the fire pot 9 is connected from a point above its grate 13 to a point below the grate 11 of the fire pot 7 by way of a cross-connecting flue 37 having therein a damper 39. The flues 33 95 and 37 are similar.

Each of the flues 33 and 37 has a connection 41 and 43 respectively with a chimney connection or breeching 45, leading to a chimney or other suitable draft inducing device (not 105 shown). The connections 41 and 43 with the cross flues 33 and 37 respectively are made at points between the fire pots 7 and 9, and the said dampers 35 and 39, respectively, whereby it is made possible to operate the fire pots 7 and 9 in parallel whenever desired and under the alternate series conditions to be de- 110

scribed hereinafter. The connections 41 and 43 carry dampers 47 and 49 respectively.

It will be evident hereinafter, that by properly setting the dampers 29, 31, 35, 39, 47 and 49, that three phases or conditions of operation may be accomplished, namely:

(1) The dampers 29, 35 and 49 may be open and the dampers 31, 39 and 47 may be shut at the same time. This condition is illustrated in Figs. 1 to 3, giving a series operation of the fire pots.

(2) Also, the dampers 29, 35 and 49 may be shut and the dampers 31, 39 and 47 may be open at the same time. This condition is the inverse of that illustrated in Figs. 1 and 3 and recited under alternative (1), above, giving inverse series operation.

(3) On the other hand, the ash pit dampers 29, 31 and the breeching dampers 47 and 49 may all be open, while the cross-connecting-flue dampers 35 and 39 are closed. This condition provides parallel operation of the fire pots.

Under condition (1), also set out in the drawings, the grate 11 has just been fired with fresh or green coal which causes smoke, while the grate 13 has had its charge burned down to a hot, smokeless coke. The result is that air is drawn in beneath the grate 11 from the inlet 23 and the volatiles, which are driven from the freshly fired coal (especially from soft coal), are passed over beneath the grate 13 and through the hot bed of coke and thence out to the chimney. This means that the volatiles are positively put into a burning or combustible condition, because they are forced to pass through the hot coke. Smoke is thus eliminated.

Under condition 2, set out above, the action is similar, except that it is the inverse, fresh coal having just previously been fired into the fire pot 9 and the charge of the fire pot 7 having been previously burned down to hot smokeless coke.

It is desirable that at sometime after firing each respective bed, that condition 3 be brought about automatically, because the fresh coal gradually ignites and sends over to the other grate such hot gases that the other grate is in danger of being burned out. Furthermore, when these conditions are reached smoking from the fresh coal has stopped, because this coal now provides its own high temperature for complete combustion. The need for series operation has ceased. Said automatic action is thermostatically controlled. Under condition (3) each furnace draws its own supply of cool air from the inlet 23 and discharges directly to the stack, the cross flues 33 and 37 having their dampers 39 and 35 closed.

The inter-connection and operation of the dampers is illustrated more particularly in Figs. 4 to 6, in which is illustrated one of a twin set of controls. Only one control is

shown because the other is a duplicate and its connection is evident.

Referring now to Figs. 4 to 6, there are illustrated diagrammatically said dampers 31, 35, and 47, which are all connected in the same operating system shown. Dampers 29, 39 and 49 are connected together in order in a similar manner (not shown).

Dampers 31 and 35 are connected to operate together by a chain and sprocket system 51 and are controllable by a chain 53 passing over a sprocket 55 on the shaft of the damper 35. The chain 53 passes over suitable guide and idler wheels 57 and 59 (above the jacket) and also over a control sprocket 61 and a sprocket 63 connected to the shaft of damper 47.

The control sprocket 61 is made fast to a ratchet member 64 carrying an arm 65 for manual setting purposes and a dog 67 normally engaged by a control pawl or click 69 pressed into a holding position by a control spring 71. The mechanism is set into the Fig. 4 position by manually bringing the arm 65 from its dotted line position to its solid line position, whereupon the pawl 69 holds the mechanism in place against the gravitational action of a weight 73 suspended from the chain 53. A secondary weight 75 is used at the other end of the chain 53 for the purpose of maintaining it taut.

The pawl 69 also forms an armature for an electromagnet 77, wired into a battery or other suitable electric circuit 79 having therein a switch 81, adapted to be closed by the action of a thermostat 83, that is, whenever said thermostat reaches a predetermined temperature. One thermostat for one of the control systems is placed in each of the cross flues 33, 37 at the region X (shown in Figs. 1 and 2). The thermostats 83 are shown diagrammatically at X in Figs. 1 and 2 for clarity.

Each thermostat 83 (Figs. 5 and 6) comprises a metal couple 85 pivotally supported at 87 and carrying at said pivot 87 an arm 89 for pressing said switch 81. The couple arm 85 rests upon a pin 91 so that when it is distorted due to increasing temperature, it causes rotation of the pivot 87 and movement of the arm 89 to close the switch 81, whereby the electro-magnet or solenoid 77 is energized and the pawl 69 pulled from under the dog 67, whereupon the descending weight 73 throws the dampers 31, 35 and 47 into positions alternate to the positions shown in Figs. 1, 2 and 4, hereinafter known as their "down" positions. The "up" position shown, corresponds to that manually given by an operator immediately after having fired the pot 7. The other dampers 29, 39 and 49 are already in "down" position such that the required series operation can be carried on and such that when the Fig. 4 damper system moves to its alternate "down" position, under

thermostatic control, that parallel operation of the furnaces or fire pots will be had as described under condition 3 above.

Parallel operation will proceed indefinitely until the fires burn out, unless the operator re-fires. Upon refiring the operator will fire the alternate pot 9 and pull the alternate damper control system (similar to the one shown in Fig. 4) into the Fig. 4 position, whereupon dampers 29, 35 and 49 will be in closed position and dampers 31, 39 and 47 will be in open position. This is because dampers 31 and 47 have automatically opened after the last firing and the damper 35 has at the same time automatically closed, while the dampers 29 and 49 are manually closed at the same time that the damper 39 is manually opened, said dampers 29, 39 and 49 being in the same type of system corresponding to that shown in Figs. 4 to 6. Each damper system controls the two inlets for one furnace and the breeching outlet of the other, as for example in Fig. 4, the system controls the two inlet dampers 31 and 35 of ash pit 17 and the breeching damper 47 of the pot 7. The corresponding damper system (not shown) controls the two inlet dampers 29 and 39 of the pit 15 and the breeching damper 49 of the pot 9.

The operation of the furnace is as follows, assuming a hot coke bed in pot 9 and a similar bed in pot 7, said pots operating in parallel. Both damper control systems are in their released positions with weights down. Hence the conditions under alternative (3), above, are maintained.

Next, the operator fires fresh coal into the pot 7 and pulls the corresponding arm or control 65, adapted to bring about resetting of the dampers 31, 35 and 47 into the positions shown in the drawings and recited under series condition (1) above. This means that the furnaces are operating in series with pot 7 as the first in series and the pot 9 as the second in the series, the unburned volatiles from the fresh coal in pot 7 passing over and through the hot-coke of pot 9. The volatiles are thus positively ignited.

After the fresh coal begins to burn without smoke the temperature of the gases increases and the corresponding thermostat 83 is moved to close the corresponding circuit 79 for permitting the described automatic change of the positions of dampers 31, 35 and 47 so that the conditions under alternative (3) again hold, that is, the furnaces are operating in parallel with the cool air coming through each grate.

At the next firing the operator fires the alternate fire pot 9 and pulls up the other corresponding lever or control to move dampers 29, 39 and 49, whereupon the conditions are reversed and series operation is had with the fire pot 9 as the first in the series and the fire pot 7 as the second in the series. This alter-

nate series operation continues until the other thermostat 83 is moved to close its corresponding circuit 79 for permitting the automatic return in positions of dampers 29, 39 and 49 so that parallel operation is again brought about, that is, dampers 29, 31, 47 and 49 are open, while dampers 35 and 39 are closed.

At the next firing, pot 7 is again fired and its control handle is moved and the cycle of operation is thus completed. It will be seen that during parallel operation both of the pair of handles 65 are in the same position and that when an operator fires one of the fire pots that he merely moves the corresponding handle 65 which may be colored or otherwise designated as belonging to the respective side of the furnace being fired. Hence, it is evident that no complications are introduced in operating the furnace.

It is to be understood that the furnaces otherwise are taken care of in the ordinary manner, such as cleaning the grates and removing ashes and the like. It is to be understood that the circuit 79 need not be energized by means of a battery but may be energized in any other suitable way.

It is understood that the thermostat need not be of the particular type indicated but may be of a type using air or steam or other medium and operating a suitable closing switch at a limiting temperature.

Furthermore, the entire furnace may be one applicable to other systems such as steam or hot water.

The forces causing damper operation need not be gravitational but may arise from springs, compressed air, hydraulic pressure or the like.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. A furnace comprising a plurality of fire pots and means for inducing a draft through said pots alternately in series and in parallel, automatic means for changing said draft from series operation to parallel operation comprising a plurality of dampers normally subject to forces for changing their setting, control means for temporarily resisting said forces, means operable at a predetermined temperature for releasing said control means so that it does not resist said forces, whereby said forces actuate said dampers to change the damper setting to provide parallel operation, and manual means for resetting the

dampers to provide series operation and for simultaneously re-applying said forces and said resisting control means.

2. A furnace comprising a plurality of fire pots and means for inducing a draft through said pots alternately in series and in parallel, automatic means for changing said draft from series operation to parallel operation comprising a plurality of dampers normally subject to forces for changing their setting, control means for temporarily resisting said forces, thermostatic means movable by temperature change due to heating of the fire pots, an electric circuit adapted to be closed by said thermostatic means upon a predeter-

mined rise in temperature and adapted upon closing to release said control means so that said control means does not resist said forces, whereby said forces actuate said dampers to change the damper setting to provide parallel operation, and manual means for resetting the dampers to provide series operation and for simultaneously re-applying said forces and said resisting control means, provided the operation of said thermostat and electric circuit will permit. 20
25

In testimony whereof, I have signed my name to this specification this 25th day of May, 1927.

SILAS BENT RUSSELL.
